UNITED STATES PATENT OFFICE.

HERMAN J. RUDULPH, OF BROOKLYN, NEW YORK, ASSIGNOR TO MERGENTHALER LINOTYPE COMPANY, A CORPORATION OF NEW YORK.

TYPE, MATRIX, SPACE, &c., FOR TYPOGRAPHICAL MACHINES.

1,122,541.

Specification of Letters Patent. Patented Dec. 29, 1914.

Application filed March 11, 1914. Serial No. 823,934.

To all whom it may concern:

Be it known that I, HERMAN J. RUDULPH, a citizen of the United States, residing at Brooklyn, in the county of Kings and State of New York, have invented certain new and useful Improvements in Type, Matrices, Spaces, &c., for Typographical Machines, of which the following is a specification, reference being had therein to the accompanying drawing.

My invention relates to type, matrices, spaces, etc., for typographical machines, which are ordinarily provided with ears, edges, or other guiding portions, which facilitate their travel in the machine and insure their proper storage. For instance, in the well-known linotype machine, matrices and spaces are formed with projecting ears at their corners, and these ears have a thickness equal to or less than that of the body portion. I have found it desirable in some instances to form these ears of greater thickness than that of the body portion, and in the specific instance illustrated, I have shown my improvements as applied to extremely thin blanks or hair spaces, although obviously they might similarly be adapted to matrices provided with characters, or in other forms of typographical machines to types or dies, as well as to matrices and spaces.

Generally speaking, I desire it to be understood that I do not limit myself to any specific form or embodiment, except in so far as such limitations are specified in the claims.

Referring to the drawing: Figure 1 is a vertical section through the lower end of the magazine of a linotype machine, wherein are stored blanks or matrices embodying my invention; Fig. 2 is a section on the line 2—2 of Fig. 1; Fig. 3 is an edge view of an assembled line as employed in tabulation; Fig. 4 is a section on the line 4—4 of Fig. 3; Fig. 5 is a section on the line 5—5 of Fig. 3; Fig. 6 is a perspective of a hair space; and Fig. 7 is a similar view of a hair space and an ordinary matrix.

Referring to Figs. 1 and 2, the matrices X and hair spaces W are stored as usual in the magazine A formed with the channel grooves A¹, and their release therefrom is controlled by the escapements B. In the ordinary construction of magazine, the width of the narrowest groove A¹ is con-

siderably greater than the thickness of the body portion of a hair space W, for instance in actual practice these dimensions are .040 inch and .014 inch respectively. Therefore, with spaces of the ordinary construction, 60 they would pass and lap each other in the channels. In order to insure their proper storage, I therefore form the spaces W (see also Fig. 6) with their ears W¹ of a thickness greater than that of their bodies, and 65 one approximating the width of the corresponding grooves A¹. In this way, I insure their proper location in the magazine channels one above another.

Fig. 7 shows my improved hair space in 70 proximity to an ordinary matrix X, it being noted that the ears X¹ of the latter are of less thickness than that of its body, thus affording the space necessary to receive the projecting ears W¹ of the space W when 75 the latter is brought into close relation to a matrix. This coöperation is well indicated in Figs. 3, 4 and 5, which illustrate an assembled line of tabular matter, comprising matrices X, wedge spacers Y, and the hair 80 spaces W. It will be noted that the thickened ears W¹ of the hair spaces project over the body portions of the adjoining matrices, and in a sense so that the latter are inclosed by the former. It will also be noted that the 85 spacers Y have only the width of the body portions of the matrices X and spaces W, so that in the event that a space W is brought into contact with a spacer Y, its ears W¹ will project beyond and inclose the spacer, 90 although this latter arrangement is not specifically illustrated in the drawing.

In Fig. 4 is shown a tabular slug Z produced from the assembled line of matrices, the slug having deep vertical notches Z¹, all 95 as well understood in the art.

I have shown my invention only in preferred form and by way of example, and as applied to a hair space in a linotype machine, but obviously many changes and variations therein, and in its mode of application, will suggest themselves to those skilled in the art, without departure from its scope. Thus, as previously stated, it may similarly be adapted to matrices or to the types or 105 dies of typesetters, typecasters, and the like.

Having thus described my invention, its construction and mode of operation, what I claim and desire to secure by Letters Patent of the United States, is as follows:

1. A type, matrix, or space adapted for circulation in a typographical machine and formed with projecting ears to support and guide it during circulation, the said ears being of greater thickness than the greatest thickness of the body portion of the type, matrix, or space. 25
2. A type, matrix, or space adapted for circulation in a typographical machine and formed with projecting ears to support and guide it during circulation, the said type, matrix, or space having a body portion whose side edges are of uniform thickness, and the projecting ears being of greater thickness than that of said side edges. 30
3. A type, matrix, or space, having a body portion of rectangular form and of uniform thickness throughout, and provided at each of its four corners with projecting ears of greater thickness than that of the side edges of said body portion. 35
4. Two coöperating type, matrices, or spaces, each formed with projecting ears, the ears of one of them being thicker than its body portion, and the ears of the other being thinner than its body portion; whereby the two may overlap one another. 35
5. A type, matrix, or space, having a body portion of uniform thickness, and formed with projecting ears of greater thickness than that of said body portion, and a coöperating type, matrix or space having its body portion seated against the body portion of the first mentioned one and inclosed by its thick projecting ears. 35

In testimony whereof I have affixed my signature in presence of two witnesses.

HERMAN J. RUDULPH.
